UNITED STATES PATENT OFFICE.

WILLIAM E. WHITE, OF CHICAGO, ILLINOIS, ASSIGNOR TO KALMAN STEEL CO., OF CHICAGO, ILLINOIS, A CORPORATION OF DELAWARE.

SLEEPER ANCHOR.

Application filed December 8, 1923. Serial No. 679,470.

My invention relates to devices for securing sleepers to concrete floors and particularly to an improvement on the construction shown in my co-pending application Serial 5 No. 521,600, filed Dec. 12, 1922.

In the construction here proposed there are numerous advantages both from the standpoint of manufacture and use. The wire element is the same as that of my previously disclosed construction and is simply made in an automatic machine. The sheet metal parts are more simply made and the assembly is quickly accomplished in a suitable machine. In the use of the device the 10 advantages are apparent, no difficulties being encountered because of the necessity for bending the metal. Thus the breakage resulting from repeated bendings is avoided. Because the desired result is secured without 15 bending the metal I am enabled to use sheet metal of heavier gauge and thereby increase the efficiency of the device by avoiding the tearing out of the fastening nails.

The invention will be more readily understood by reference to the accompanying drawings, wherein,

Fig. 1 is a transverse sectional view through a body of concrete showing the application of my sleeper anchor thereto;

Fig. 2 is an enlarged elevation of the device;

Fig. 3 is a sectional view on the line 3—3 of Fig. 2, and,

Fig. 4 is a plan view thereof.

In the drawings it will be seen that the 35 device comprises essentially an anchor element consisting of a length of wire bent to provide V-shaped side portions 10, 11, joined at the upper extremities of the Vs by horizontal portions 13 which lie parallel to and at the surface of the concrete A, shown in Fig. 1. The connecting portions 13 are joined by a strip of metal 14, the ends of which are hooked or crimped into cylindrical form. This strip acts to prevent 40 spreading of the V-shaped anchors and as a limit stop for determining the extent to which the anchors are projected into the plastic concrete.

The means for engaging the sleepers indicated at B in Fig. 1, consist of strips of metal 15, 16, in the form of wings perforated 50 at their upper ends and at their lower ends crimped or hooked around the connecting

portions 13, the metal being rolled as at 17, 55 to provide in effect a hinge. Preferably this hinge is encompassed within the rolled portion 18 of the connecting strip 14. The wings or strips 15 are handled, shipped and installed in the dotted line position of Fig. 2. After having been inserted into operative 60 position and the concrete hardened, the wings are swung on their pivots to the perpendicular position shown in Fig. 1 and are adapted to receive the sleepers B between them. 65

The construction is such that after installation and the hardening of the concrete the hinged elements are firmly incorporated in the structure. In actual practice the concrete will more or less flow around the hooked end 18, which encompasses the hinge and thus form a firm and rigid connection which cannot easily be broken.

The device is of extreme simplicity and its use does not involve the bending of the material composing the wings. This enables the use of slightly heavier material and avoids the possibility of tearing out of the nails after the installation of the sleepers. 70 Much the same results may be secured by eliminating the connecting strip 14 and that construction is contemplated under some circumstances. This and other modifications I consider within the scope of my invention.

In the claims the word "hinge" is used 75 in its accurate sense and is intended to distinguish over a construction in which a hinge effect is secured by bending the metal.

I claim:

1. In a device of the class described, the 90 combination of a pair of anchor elements, rods connecting the same, wings hinged to said rods and adapted to be disposed in a position flat on a cement surface or perpendicular thereto in vertical planes at right 95 angles to the planes of the anchor elements in order to provide means of attachment to a sleeper.

2. In a device of the class described, the 100 combination of a pair of anchor elements and cylindrical connecting members, and wings hinged to said connecting members and adapted to be disposed in a position flat on a cement surface or perpendicular thereto in order to provide means of attachment to a sleeper, and means for tying together said cylindrical members and serving 105 also as a stop for limiting the extent of

insertion of said anchor elements in the cement.

3. In a device of the class described, the combination of a pair of anchor elements and cylindrical connecting members, and wings hinged to said connecting members and adapted to be disposed in a position flat on a cement surface or perpendicular thereto in order to provide means of attachment to a sleeper, and means for tying together said cylindrical members and serving also as a stop for limiting the extent of insertion of said anchor elements in the cement, the ends of said tying members being bent over the hinge of said wings.

4. In a device of the class described, the combination of a single wire bent to provide a pair of V-shaped anchor elements, connecting wires between the upper ends of respective anchors, and sheet metal wings having their ends crimped around said connecting wires to provide a hinge.

5. In a device of the class described, the combination of a single wire bent to provide a pair of V-shaped anchor elements and connecting wires between the upper ends of respective anchors, sheet metal wings having their ends crimped around said connecting wires to provide a hinge, and a sheet metal tie extending horizontally between respective connecting wires, the ends of the tie be-

ing crimped over the hinge portion of the wings.

6. In a device of the class described, the combination of a single wire bent to provide a pair of V-shaped anchor elements, connecting wires between the upper ends of respective anchors, sheet metal wings having their ends crimped around said connecting wires to provide a hinge, and a horizontal member secured to and joining said connecting wires and acting as an insertion limit stop.

7. In a device of the class described, the combination of a single wire bent to provide a pair of V-shaped anchor elements, and wings having a hinge connection with the connecting wires and adapted to lie in a vertical plane at right angles to the vertical plane of the anchor elements.

8. In a device of the class described, the combination of a single wire bent to provide a pair of V-shaped anchor elements, wings having a hinge connection with the connecting wires and adapted to lie in a vertical plane at right angles to the vertical plane of the anchor elements, and a member secured to and joining said connecting wires and acting as an insertion limit stop.

Signed at Chicago, Ill., this 5th day of December, 1923.

WILLIAM E. WHITE.
